GARMENT PRESSING MACHINE

Edwin H. Zacharias, Reading, Pa.

Application December 12, 1930, Serial No. 501,958

10 Claims. (Cl. 68—9)

This invention relates to garment pressing machines particularly of the type in which there are two members adapted to receive between them a garment to be pressed, and at least one of the members is movable vertically and not thru an are.

The principal object of the present invention is to provide an exceptionally sturdy garment pressing machine in which there is no tendency for the garment to be wrinkled as the two ironing members come together as is the case in all machines where the upper iron moves about a horizontal pivot.

An important object of the invention is so to mount a slidable supporting bar upon anti-friction devices that it can be moved freely to chosen position with slight effort when a garment or other object is not being pressed and in which these anti-friction members are relieved of all stress when the bar is under load.

A further object of the present invention is the provision of an automatic latch which can be set to lock the upper and lower irons together with a garment between them so to exert a chosen predetermined pressure, without attention on the part of the operator.

A still further object of the invention is to mount the upper iron so that it may have a swiveling action, the more readily to press seams and in which no stress is ever taken by the swinging means when the iron is engaged by a garment beneath it, whether the upper iron is moved downwardly or the lower iron is moved upwardly.

In garment pressing machines of the most popular type some little criticism has been directed to the slipping action of the two irons which is inherent in all machines where the upper iron is pivoted about a horizontal axis, usually back of the table. In such a case the upper iron must necessarily move forward toward the operator as it is lowered and this causes a forward movement of the garment on the lower iron as the two irons come together. This is not only somewhat harmful to the garment but more important still from a pressing standpoint this slip due to the arc of movement will frequently cause wrinkles in the garment being pressed. This objection is entirely eliminated in the present device because the upper iron does not move out of its horizontal plane as a unit altho it has freedom of movement at its front and rear by virtue of the swivel engagement between the upper iron and the horizontally slidable bar which carries it.

In previous attempts to utilize an upper iron carried by a sliding bar it has been found that

some extra precaution must be taken to provide the necessary strength of the parts as the punishment upon the bar and the parts which carry the bar is very great particularly where the leverage is very long. This cannot be obviated but the stresses can be minimized by a proper disposition of the swiveled carrier which in the present case is so constructed that the supporting surface for the iron carrying bar is preferably at least three times as long as the distance from the bar to the vertical pivot about which the carrier swings.

Another objection to the previous iron-carrying bars has been that it was entirely too hard to move them into position. This objection has been entirely eliminated by the provision of two, four, or even more anti-friction bearings which are positioned so as to guide the movement of the bar in any unloaded position and yet when pressure is applied to the iron either by moving the upper iron down or by moving the lower iron upward, the bar is instantly moved out of contact with the anti-friction members which therefore take no load save the relatively light load of the iron and the bar.

In the drawings:

Figure 1 is a side elevation.

Figure 2 is a front elevation.

Figure 3 is a top plan view of the carrier.

Figure 4 is an elevation of the carrier.

Figure 5 shows the construction of the automatic latch.

Figure 6 is a detail of the iron swivel.

The front section 10 of the frame consists of a tubular standard which houses the vertically reciprocating plunger 11 carrying the table 12 which thru the two I-beams 13 supports the steam, gas, or electric heated lower iron or buck 14. In the form illustrated the standard 10 is expanded at its bottom to form a circular pedestal 15 which furnishes the principal support of the device altho the lateral legs 16 and the rear leg 17 are preferably secured to the floor, and aid materially in strengthening the stand. The upright standard rising from the rear portion of the frame is of I-beam section having a central web 18 reinforced by rather sturdy front and rear flanges 19 extending laterally in both directions. This I-beam section of the casting ends at its upper portion in a forked bearing, the upper fork or bracket being given the numeral 20 and the lower fork or bracket being given numeral 21. Between these forks is quite snugly received the carrier denoted as a whole by the numeral 25 and carrying in some semi-permanent manner as, for example,

by a set screw 25', the heavy pivot 21'. I prefer to recess the carrier as at 26 to receive an anti-friction bearing 27 to permit very ready turning of the carrier and its pivot 21' in the arms or brackets of the forked end of the frame.

10 The means for moving the irons together may take any form and either or both irons may be moved but I desire that the movable iron shall move vertically and not thru an arc. As shown
15 the means for elevating the table 12 and lower iron 14 follow in general principles the mechanism illustrated in my application Serial No. 739,090 filed Sept. 22, 1924, patented November 17, 1931, Patent No. 1,832,521, utilizing a treadle lever 30 pivoted between its ends in four lugs 31 and thru two links 32 operating two levers 33 which turn about a pivoting fulcrum block 34 which is vertically movable into chosen adjusted position by means of the screw 35 bearing against
20 the flange 36. Centrally thru both levers 33 is a shaft 37 which also passes thru or extends from the plunger 11. By depressing the treadle 30, the table and with it the lower iron 14 is elevated into contact with the upper iron 40 should
25 that member be in normal pressing position. This construction I much prefer to having the table stationary and vertically moving the bearings 20 and 21.

Referring particularly to Figures 3 and 4 a very important element of the present invention is the carrier 25 which in plan view appears as a hollow three-sided casting strengthened by the rib 39 and open at its front face, having a recess there in to receive the bar 41 which carries at its forward end the upper iron 40. It will be noted from Figure 4 that the bearing surface for the bar 41 is not continuous, being cut away as at 43, 44 and 45 at the bottom and at 46 and 47 at the top to save machining, leaving at the left hand upper side the important bearing surface 48 and at the lower right hand side the equally important bearing surface 49 into engagement with which the bar is brought by upward pressure on the iron 40.

45 The anti-friction members 50 and 51 are mounted on studs 52 and 53 so located that the peripheral edge of the outer member of the bearing shall project into the groove in the carrier a slight distance beyond the planes of the bearing surfaces 48 and 49, and these two bearings, with the optional similar anti-friction member 55 on stud 56 taking all of the weight of the iron and bar as the iron is moved in the carrier, the member 55 coming into use as the bar is telescoped into its recess. The carrier also is provided with a pair of anti-friction members 58 and 59 mounted on vertical studs 60 and 61 so positioned that both shall engage the bar 41 at all times when the iron 40 is free. These two ball bearing devices are provided because in the mounting of the iron 40 on the bar 41 it is desired that the rear or heel portion of the iron shall be heavier than the front portion of the iron and as a natural consequence there is a tendency for the bar to turn its top edge towards the closure plate 63 and its rear bottom edge toward the main pivot 21', this tendency being resisted by these two anti-friction devices on the vertical studs, which therefore facilitate movement of the bar.

70 The specific mounting of the upper iron 40 on the bar 41 is seen in Figure 6. A swivel head bolt 64 engages quite loosely a spherical recess 65 in the handle 66 of the iron 40 and passes snugly thru the bar 41, carrying at its upper end the nut 75 61, also holding in place the stop 68. It will thus

be seen that the iron 40 may be tilted in any direction about its supporting bolt 64 but that when the lower iron 14 is in pressing relation the bolt 64 is relieved of all stress and the entire stress is transmitted to the bar 41 from the top surface 69 of the lower section of the handle of the iron, it being understood that the bolt 64 is quite loose in relation to the handle or the iron and merely holds the iron against gravity.

Referring particularly to Figure 5 it is highly desirable that a machine of the type described have some definite means for automatically securing a desired pressure and this is accomplished by pivoting on the frame 10 about pivots 10 and 11 a rack bar 12 and a lever 13 and mounting upon the pivoted treadle 30 a small catch 14. The lever 13 is weighted as at 15 so as to tend to throw the pedal 16 upward and the other arm of this lever carries a screw 17 which adjustably engages the rear edge of the pivoted and toothed rack 12. When the two irons are separated the top surface of the treadle 30 is considerably above the level of the elevated pedal 16 and the operator has his foot upon the treadle 30 with the toe portion of his shoe above and slightly rearward of the pedal 16. As the operator presses down the treadle 30 his foot will therefore come into contact with the pedal 16 and this will turn the lever 13 about its fixed pivot 11 on the frame causing the screw 17 to engage the loosely hanging rack 12 and move it forwardly into engagement with the plate 14 carried by the treadle, automatically latching the treadle at the chosen degree of pressure which can be readily regulated by movement of the screw 17 which can be locked by the nut 18. To release this latch it is merely necessary to press on the treadle 30 without simultaneously pressing on the pedal 16 whereupon the weighted end 15 will free the rack 12.

When it is desired to press a garment, the carrier is thrown far to the right as seen in Figure 1 moving the upper iron 40 entirely to one side and, if desired, well back of the buck 14. The operator is then free to place the garment on the buck in chosen fashion without any interference by any mechanism. This is made possible by the right triangular shape of the carrier and also by mounting it on the right side of the frame as shown best in Figure 2. In this figure it is seen that when the long side of the carrier and therefore the bar 41 is perpendicular to a plane thru the center line of the buck 14, the iron is at the extreme right end of the buck and is well out of the way for the garment arranging step in the pressing process. After placing the garment as desired, the operator now swings the carrier to the front and brings the iron into contact with the garment by depressing the treadle 30 to give the required pressure. As long as the pressure exerted thru the treadle 30 is slight the weight of the iron is carried by the anti-friction devices 50 and 51 and 55 and at such times the iron can readily be tilted as may be desired, for example, in the opening up of a seam. When greater pressure is exerted against the treadle 30 the iron becomes stationary in a horizontal position and the pressure is transmitted direct to the bar 41 which engages the groove in the carrier along the rather ample finished surface 48 raising the bar free of the anti-friction member 50 and simultaneously tilting the bottom surface of the bar 41 into firm contact with the lower rear finished surface 49 and away from the anti-friction device 51 above it. Because of the cut away spaces 44 and 45 on each side of the anti-fric- 75

tion bearing 55, this member likewise is freed of all stress during the pressing operation. The anti-friction devices 58 and 59 being mounted on vertical pivots cannot and do not take any stress when pressure is exerted on the treadle 30. While I prefer to finish the surfaces 80, 81 and 82 at the bottom of the groove in the carrier which receives the bar 41, and the surface 83 at the top, these surfaces are not actually needed and I find that after a certain amount of use of the machine the bar 41 does not contact with these surfaces. The surface 84 is, however, highly desirable and I find that the bar engages this surface under load even after a very considerable amount of wear. If desired, the surfaces 48 and 49 may be sloped, say one or two degrees downward to the right in Figure 4 but I do not find this necessary in practice as I only project the wheels of the roller bearings into the recess by a sixtieth fourth of an inch, just enough to let the bar clear the finished surfaces readily under no load except the weight of the iron.

What I claim is:

1. In a garment pressing machine, an upper iron, a vertically movable lower iron, a depressible treadle for raising said lower iron to engage said upper iron, a latch, and means for operating the latch pivoted to lie below the level of the treadle when the treadle is in an elevated position and adapted to lie above the top of the treadle when the treadle is in a lowered position, said means lying adjacent said treadle to be engaged by the foot of the operator as the treadle is depressed whereby the operator may set the latch without shifting or otherwise moving his treadle engaging foot and is thus able to exert a maximum pressure on the treadle while giving his entire attention to the garment under pressure.
2. In a garment pressing machine, a frame having a relatively massive standard rising at the rear of the machine, said standard carrying on the right of the center of the machine a pair of integrally connected vertically spaced bearings, a laterally extending lower iron movably carried by the frame in front of the bearings for vertical movement, a carrier pivoted by a pin journaled in said bearings, a bar slidable in said carrier, an upper iron carried by the bar, said upper iron telescoping its bar into the carrier as the iron moves toward the center of the lower iron from either end of the lower iron, said pin being removably secured to the carrier whereby the carrier may be removed and installed by the removal and replacement of the pin.
3. A supporting device for the upper iron of a garment pressing machine in which the lower iron is elevated into pressing engagement with the upper iron, consisting of a carrier substantially right triangular in plan, pivoted near the right angle and having a guide-way of substantially the same length as and parallel to the hypotenuse, a bar slidable in said guide-way, the axis of the pivot being spaced a certain distance to one side of the front to back centerline of the machine, and said guide-way being spaced at substantially twice the distance from said axis.

4. In a garment pressing machine, a frame, a carrier mounted to swing about a vertical pivot, a bar slidable in said carrier, an iron mounted at the free end of the bar to turn about a vertical pivot, to be movable about a plurality of horizontal axes through the top of the iron and be movable to a slight extent vertically with respect to said bar so that said iron has universal movement in a horizontal plane and when the iron is pressed upwardly it engages firmly said bar. 10

5. The device of claim 4 in which the iron is swivelly mounted on its vertical pivot to tilt thereon from said horizontal plane as it moves, as in opening a seam.

6. A carrier for a horizontally sliding iron supporting bar on which the iron is unevenly mounted so as to cause the bar to tend to turn about a horizontal axis parallel to the longitudinal center line of the bar, consisting of a body having a channel across one side to receive loosely said bar and having an anti-friction device near one end of the carrier and on one side of the channel, and another anti-friction device near the other end of the carrier and at the other side of the channel, one of said anti-friction devices touching the bar near an upper edge in a manner to resist said turning and the other touching the bar near a lower edge. 15

7. A latch for a garment pressing machine consisting of a toothed rack pivoted to the frame, 30 a lever having a pedal at one end and a rack engaging portion at the other end, pivoted between its ends to the frame, a treadle pivoted to the frame to move past the pedal, a catch carried by the treadle in the path of the teeth of the rack 35 as it is moved by the lever, said pedal lying in the path of an operator's foot as the treadle is depressed whereby after an angle of movement of the treadle the pedal is engaged to move the rack into locking position with the treadle carried latch. 40

8. In a garment pressing machine having a garment supporting buck and an elongated iron supporting bar thereabove, a supporting frame, a carrier for said bar comprising a sleeve portion in which said bar is adapted to telescope and a pivoting portion adapted to be connected to said frame, said connection being to the right side of the frame with respect to the front of the machine, and the connection and sleeve being so 45 spaced that when said sleeve is perpendicular to the buck the iron is at the extreme right end of the buck in which position the iron may be quickly moved after each work stroke and is thus always in position for a second stroke. 55

9. The device of claim 4 in which the pivot is connected to the iron to one side of the center of gravity so that the nose of the iron normally tilts upward when the iron is in suspended position. 60

10. The device of claim 4 in which the pivot is connected to the iron at a point so that the iron normally tilts about a transverse axis when in suspended position.

EDWIN H. ZACHARIAS. 65
